LOCKING DEVICE

Aaron Shatkin, Brooklyn, N. Y.

Application June 1, 1933, Serial No. 673,811

9 Claims. (Cl. 120—9)

My present invention relates to locking devices, particularly of the type adaptable in collapsible housings for writing instruments.

The objects of this invention are to provide a novel and improved locking device of the character mentioned, which locks the housing aforesaid when the latter is collapsed, which requires no manual rotary motion either at locking or unlocking of the telescopic housing elements, and which is simple in construction, certain in operation and convenient in use.

To attain these objects, in an embodiment of my present invention in a collapsible housing for writing instruments, which housing includes a series of telescopically associated tubular elements, I provide a headed member which is secured to the innermost tubular element of the housing; the head of which member projects within the housing towards the outermost member, a pair of gripping elements, mounted in the outermost tubular member, adapted to close in upon and secure the said head between them when the telescopic housing is closed or collapsed against the action of a spring which acts upon the gripping elements to maintain their closed condition, and to unlock or release the grip upon said headed member, I provide a button member which is slidably mounted at the extremity of the outermost tubular member of the housing, which button when pushed inwardly against the action of a spring, is adapted to move the gripping elements to free their hold, whereupon the housing becomes extended.

This invention is capable of numerous forms and various applications without departing from the essential features herein disclosed. It is therefore intended and desired that the embodiment shown herein be deemed illustrative and not restrictive, and that the patent shall cover whatever features of patentable novelty exist in the invention disclosed; reference being had to the appended claims rather than to the specific description herein, to indicate the scope of the invention.

In the accompanying drawing, forming part of this application, similar characters of reference indicate corresponding parts in all the views.

Fig. 1 shows substantially, a central longitudinal section through a fully extended collapsible housing for writing instruments, which is equipped with an embodiment of the locking device which is the subject of this application.

Fig. 2 shows a similar section when the housing is collapsed and locked.

Fig. 3 is an enlarged fragmentary section showing the embodiment of the locking device.

Fig. 4 shows in perspective the gripping elements and the headed element of the locking device.

Fig. 5 is a fragmentary central longitudinal section through an extended housing, showing the construction to incorporate my locking device, when the housing includes a magazine for leads.

Fig. 6 shows in perspective the releasing button provided with an eraser which is included in the embodiment shown in Fig. 5.

Fig. 7 shows in perspective the inner end tubular element included in the embodiment shown in Fig. 5.

In the drawing, the numeral 10, designates generally a collapsible housing for writing instruments, comprising the concentric tubes 11, 12 and 13, which slide co-axially within one another. Provision is made by the inward beads 14, and the outward beads 15, to prevent the several tubes from coming apart, and the end 16, of the tube 12, is drawn in a little so as to prevent said tube 12, from sliding out when the housing 10 is collapsed; said reduced end being unable to pass the tube 11. A head element 17, is set into the tube 11, to project therefrom at its free end, and a washer 18, is secured within the tube 11, close up against the head element 17. Also, inside the tube 11, is secured a washer 19, having fixed therethrough, a coil 20. Secured within this coil 20 and protruding therefrom into tube 12, is a shank 21, which terminates in a head element 22, extending towards tube 13. Within the tube 13, a washer 23 is free to slide, which is secured to an end of a spring 24; the other end of which spring rests on the washer 19.

A hubbed bushing, generally designated by the numeral 25, having a central bore 26, is countersunk at its hub end to provide the tapering surface 27, and is counter-bored at its other end to provide the seat 28. The tube 13, terminates in an enlarged portion 28, within which is secured the member 25, by bending over the end 29, of the enlarged portion 28; the hub of member 25 thus being within the tube 13, so positioned that the surface 27 slopes towards the end 28 of the tube 13.

Resting on top of the washer 23, and through the bore 26, of member 25, are a pair of gripping elements 30, in contact with each other at the vertex lines 31, of their respective angled surfaces 32 and 33; a steel ball 34, being set within the semi-spherical sockets 35 on said vertex lines, 110

to facilitate the pivotal movement of these gripping elements 30, with respect to each other. The head 22, of the member 21, is adapted to be held between these gripper elements 30, within 5 the opposite sockets 36, to maintain the housing 10 in closed condition. Each of these gripper elements 30, at the lower end, has an outwardly extending sloping portion 37, in contact with the tapering surface 27 of the member 25, while the 10 other end of each of these gripping elements 30, is individually tapered, as indicated by the numeral 38.

A button member 39, terminating in a flange 40, which is set free to slide within the counter-bore of the member 25, against the action of a spring 41, interposed between said flange 40 and the seat 28, serves as the terminal of the housing 10, whereto is secured the chain link 42, for attachment of either a chain or ribbon, as the user 15 may desire. A ferrule 43, about the shank of the button member 39, closes the end of the tube 13, and is secured thereabout by turning inwardly the end 44. It is to be noted that the tapered ends 38 of the gripping elements 30, are positioned within a conical socket 45 bored in the flanged end of the button member 39.

When it is desired to build the housing with provision for the storing of leads and to provide other features as hereinafter indicated, the following modification in construction is followed. In place of the tube 13, is a tube 45, about which is concentrically secured the magazine tube 46; leads being stored within the space 47 formed between these tubes. Between a pair of annular beads 48, spun inwardly in tube 45, is secured the bushing element 49, the lower end of which has an inwardly sloping surface 50. Along lengthwise diametrically opposite tracks 51, dented in the tube 45 above the beads 48, is slidably mounted the member 52; the said tracks fitting into the surface channels 53, which are cut lengthwise along the sides of member 52. Integral with this member 52, is a reduced portion 54, provided with a conical bore 55. A spring 56 is interposed between the element 49 and the member 52. The tube 45 is closed by having its upper end spun over inwardly, having the hole 57, however, for the passage of the shank of the button member 58. The top end of the tube 45, is exteriorly threaded to receive cap 59, which serves to close the magazine chamber 47. Into a threaded bore 61, in the member 52, fits the threaded end of the shank of the button member 58, into which end and extending therefrom, is an eraser 60.

Writing mechanisms for either mechanical pencils or fountain pen devices are mounted within the tube 11. Such constructions and mountings are well known, and therefore are not shown. The coil 20, may be part of pencil mechanisms, but in any event, the member 21 must be secured in any suitable manner to either tube 11, or the head 17, or to any component fixedly secured to either of these.

In operation, the action of spring 24, distends the housing 10 and presses the gripping elements 30 into the member 25, whereby ends 37 come closer together in their contact with the sloping surface 27, while ends 38 of the gripping elements 30, spread apart within the conical bore 45 of the button member 39.

To lock the housing, the button 39, and the head 17 are brought towards each other whereby the housing is collapsed. The manual push of the button 39 overcomes the action of the spring 24, shifts the gripping elements 30 in the di-

rection of its motion, bringing the ends 38 together within the conical bore 45, whereby the lower ends of the elements 30 are spread apart to admit the head 22, within the sockets 36. Now holding the housing 10 collapsed and momentarily releasing hold of the button 39, will cause spring 24 to push the gripping elements 30 into member 25, whereby the hold onto the head 22 will be secured, and the shank 21 will be gripped.

To open the housing, push the button 39 towards the head 17, against the spring 41, whereupon the ends 38 of the gripper elements 30 will come together within the conical bore 45, whereupon the head 22 will be released from the hold of the gripper elements 30, and spring 24 will force the extension of the housing 10 to its open length.

In the embodiment shown in Fig. 5, since the element 52, is restrained from rotary motion, the button 58, can be easily unscrewed when it is desired to use the eraser 60. In this modified construction, it is evident that the locking device operates in a manner precisely the same as in the construction shown in Fig. 1.

I claim:—

1. In combination with a collapsible housing for writing instruments which includes telescopic tubular elements, a gripping means, normally in closed position, mounted within an end tubular element of the housing, a shank member associated with the other end element of the housing, adapted to be held by the gripping means when the housing is collapsed and said shank member admitted in the gripping means, a means to open the gripping means for the admission of the shank member therein and its release therefrom, and a flexible means mounted within the housing adapted to extend the telescopic tubular elements aforesaid, upon release of the shank member from the hold of the gripping means.

2. In combination with a collapsible housing for writing instruments which includes telescopic tubular elements, a pair of gripping elements pivotally related with each other, mounted within an end tubular element of the housing, and normally in closed position, means to move the gripping elements into open position, a shank member associated with the other end element of the housing, adapted to be held between the gripping elements when the housing is collapsed and said shank member is admitted between the gripping elements, and a flexible means mounted within the housing adapted to extend the telescopic tubular elements aforesaid, upon release of the shank member from the hold of the gripping elements.

3. In combination with a collapsible housing for writing instruments which includes telescopic tubular elements, a pair of gripping elements pivotally related with each other, mounted within an end tubular element of the housing, and normally in closed position; each of said gripping elements being provided with a socket, means to move the gripping elements into open position, a headed member associated with the other end element of the housing, adapted to be held between the gripping elements when the housing is collapsed and the head of said member is admitted within the sockets in the gripping elements, and a flexible means mounted within the housing, adapted to extend said telescopic tubular elements upon release of the headed member from the hold of the gripping elements.

4. In combination with a collapsible housing for writing instruments which includes telescopic tubular elements, a pair of gripping elements pivotally related with each other, mounted within an end tubular element of the housing, and normally in closed position; each of said gripping elements being provided with a socket, means to move the gripping elements into open position, a headed member associated with the other end element of the housing, adapted to be held between the gripping elements when the housing is collapsed and the head of said member is admitted within the sockets in the gripping elements, and a flexible means mounted within the housing, adapted to extend said telescopic tubular elements upon release of the headed member from the hold of the gripping elements.

5. In combination with a collapsible housing for writing instruments which includes telescopic tubular elements, a pair of gripping elements pivotally related with each other, mounted within an end tubular element of the housing, and normally in closed position; each of said gripping elements being provided with a socket, means to move the gripping elements into open position, a headed member associated with the other end element of the housing, adapted to be held between the gripping elements when the housing is collapsed and the head of said member is admitted within the sockets in the gripping elements, and a flexible means mounted within the housing, adapted to extend said telescopic tubular elements upon release of the headed member from the hold of the gripping elements.

- ping elements pivotally related with each other, mounted within an end tubular element of the housing and normally in closed position, a button member extending from and slidably mounted within said end tubular element, adapted upon being manually slid into said tubular element, to move the gripping elements into open position, a spring to shift the button element to its outermost position with respect to the tubular element with which it is associated, a shank member associated with the other end element of the housing, adapted to be held between the gripping elements when the housing is collapsed and said shank member is admitted between the gripping elements, and a spring mounted within the housing, adapted to extend the telescopic tubular elements aforesaid, upon release of the shank member from the hold of the gripping elements when the button member is shifted to open the gripping elements.
5. In combination with a collapsible housing for writing instruments which includes telescopically associated tubular elements, a pair of gripping elements pivotally related with each other, mounted within an end tubular element of the housing, and normally in closed position; each of said gripping elements being provided with a socket, a button member extending from and slidably mounted within said end tubular element, adapted upon being manually slid into said tubular element, to move the gripping elements into open position, a spring to shift the button element to its outermost position with respect to the tubular element with which it is associated, a headed member associated with the other end element of the housing, adapted to be held between the gripping elements when the housing is collapsed and the head of said member is admitted within the sockets in the gripping elements, and a spring mounted within the housing, adapted to extend the telescopic tubular elements aforesaid, upon release of the headed member from the hold of the gripping elements when the button member is shifted to open the gripping elements.
6. In combination with a collapsible housing for writing instruments which includes telescopically associated tubular elements, a pair of gripping elements pivotally related with each other, mounted within an end tubular element of the housing, a shank member associated with the other end element of the housing, adapted to be held between the gripping elements when the housing is collapsed and said shank member is admitted between the gripping elements, a spring mounted within the housing acting to close the gripping elements and adapted to extend the telescopic elements aforesaid upon release of the shank member from the hold of the gripping elements, and means to shift the gripping elements into open position.
7. In combination with a collapsible housing for writing instruments which includes telescopically associated tubular elements, a pair of gripping elements pivotally related with each other, mounted within an end tubular element of the housing; each of said gripping elements being provided with a socket, a headed member associated with the other end element of the housing, adapted to be held between the gripping elements when the housing is collapsed and the head of said member is admitted within the sockets in the gripping elements, a spring mounted within the housing acting to close the gripping elements.
8. In combination with a collapsible housing for writing instruments which includes telescopically associated tubular elements, a bushing member, having an inwardly sloping surface, secured within an end tubular element of the housing, a pair of gripping elements pivotally related with each other intermediate their ends, slidably mounted within the bushing member; one end of each of the gripping elements sloping outwardly at the inwardly sloping surface of the bushing member, and each of their other ends being tapered and spaced, a button member, provided with a tapered socket, slidably mounted within said end tubular element of the housing and extending therefrom; the tapering spaced ends of the gripping elements being positioned to be admitted within the socket of the button member when the latter is manually slid in their direction to bring said ends together whereby the gripping elements are shifted into open position, a spring mounted within the housing to act on the button member to shift the latter to its outermost position with respect to the tube with which it is associated, a shank member associated with the other end element of the housing, adapted to be held between the gripping elements when the housing is collapsed and said shank member is admitted between the gripping elements, and a spring mounted within the housing, acting to close the gripping elements and adapted to extend the tubular elements of the housing upon release of the shank member from the hold of the gripping elements.
9. In combination with a collapsible housing for writing instruments which includes telescopically associated tubular elements, a bushing member, having an inwardly sloping surface, secured within an end tubular element of the housing, a pair of gripping elements pivotally related with each other intermediate their ends, slidably mounted within the bushing member; one end of each of the gripping elements sloping outwardly at the inwardly sloping surface of the bushing member, each of their other ends being tapered and spaced, and each of said gripping elements being provided with a socket, a button member provided with a tapered socket, slidably mounted within said end tubular element of the housing and extending therefrom; the tapering spaced ends of the gripping elements being positioned to be admitted within the socket of the button member when the latter is manually slid in their direction to bring said ends together whereby the gripping elements are shifted into open position, a spring mounted within the housing to act on the button member to shift the latter to its outermost position with respect to the tube with which it is associated, a headed member associated with the other end element of the housing, adapted to be held between the gripping elements when the housing is collapsed and the head of said member is admitted within the sockets in the gripping elements, and a spring mounted within the housing, acting to close the gripping elements and adapted to extend the tubular elements of the housing upon release of the headed member from the hold of the gripping elements.

AARON SHATKIN.
